UNITED STATES PATENT OFFICE.

SOLOMON GERMAN, OF MONKTON, MARYLAND.

FIRE SHIELD AND EXTINGUISHER.

No. 862,152.

Specification of Letters Patent.

Patented Aug. 6, 1907.

Application filed June 15, 1906. Serial No. 321,811.

To all whom it may concern:

Be it known that I, SOLOMON GERMAN, a citizen of the United States, and resident of Monkton, in the county of Baltimore and State of Maryland, have made 5 certain new and useful Improvements in Fire Shields and Extinguishers, of which the following is a specification.

This invention is an improvement in apparatus designed especially for the protection of buildings from 10 fire and for use in extinguishing the fire; and the invention consists in certain novel constructions and combinations of parts as will be hereinafter described and claimed.

In the drawings, Figure 1 is a front elevation, and 15 Fig. 2 is a side elevation or edge view of an apparatus embodying my invention. Fig. 3 is a detail longitudinal section, partly broken away, of one of the sectional telescopic uprights. Fig. 4 is a detail cross section on about line 4—4 of Fig. 3. Fig. 5 is a detail 20 cross section on about line 5—5 of Fig. 3. Fig. 6 is a detail side view, partly in section, showing the connection between the sections of the uprights and the shield sections. Fig. 7 is a detail cross section on about line 7—7 of Fig. 3. Fig. 8 is a detail top plan view of 25 one of the top platforms; and Fig. 9 illustrates the construction whereby the invention may be utilized for supporting a scaffold and for fire escape purposes.

In carrying out my invention, I seek to provide in connection with uprights, shield sections extending 30 between the same and preferably made of fire-proof material, and adapted to protect the building, upon which the improvement may be used, from fire when an adjacent building is burning. As shown, the uprights A are composed of a series of sections A', A², A³ 35 and A⁴, the number of which may be manifestly varied as desired. These uprights are sectional and telescopic, and the uprights are adapted to be extended from the collapsed position shown in Fig. 3, to the extended position shown in Figs. 1 and 2, by fluid pressure. 40 This may be air pressure if desired, or it may be preferably water, supplied through a hose B to a suitable connection A⁵ at the lower end of the lower section A', a drain cock A⁶ being provided to relieve the pressure when it is desired to collapse the uprights.

45 At the lower end of the uprights I provide pick points A⁸ which may, in the position of the uprights shown in Fig. 2, enter the ground and anchor the uprights in place, and to one or both sides if desired of the pick points I provide rollers A⁹ to engage the ground when 50 the apparatus is tilted so the apparatus may be readily

moved from point to point and then when thrown to upright position will be anchored by the pick points as shown and before described.

The sections of the telescopic uprights are provided at their upper ends with collars a', a², a³ and a⁴, and 55 each of these collars, except the upper one a⁴, is provided with the laterally projecting lugs a⁵—see Fig. 6—between which are secured the brackets C' and C² at the upper and lower edges of the shield sections C by means of a pin or bolt C³ passing through coincident 60 openings in the said parts, as best shown in Fig. 6 of the drawing. By this construction the sections may be readily secured and may be conveniently released when desired, and in practice the sections may be applied as the uprights are extended by the application 65 of fluid pressure, as will be readily understood from the drawings. The several sections of the telescopic uprights are also provided at their upper ends with inwardly projecting flanges a⁶—see Fig. 3—which are abutted by outwardly projecting portions adjacent to 70 the lower ends of the next inner sections to limit the opening movement of the uprights, and these flanges a⁶ may preferably be provided on the collars a', a², a³ and a⁴, as will be understood from Fig. 3 of the drawings.

At their lower ends, the telescopic sections, except the 75 lower or base one, are provided with upwardly facing shoulders a⁷ on their outer sides, which are preferably provided by screwing the collars upon the lower ends of the tubular sections, as shown in Fig. 3, and above these shoulders I provide one or more bands a⁸, a⁹, and 80 interpose packing rings a¹⁰ to prevent leakage between the adjacent tubular sections. This construction is duplicated throughout the series of sections, and is clearly illustrated in Fig. 3 of the drawings.

The lower or base sections A' are provided at their 85 upper ends preferably on their collars a', with lateral lugs d to which are pivoted the upper ends of the props D, which props are preferably made in sections with their lower sections D' pointed at their lower ends and 90 slidable at their upper ends upon the upper sections and provided with clamp screws D² by which they may be held in any desired position. These props operate to steady the telescopic uprights in position when applied as shown in Figs. 1 and 2 of the drawings.

The upper sections a⁴ of the uprights are provided at 95 their upper ends with lateral lugs E' for guy lines E—see Figs. 3 and 9—and are also provided at said upper ends with rope pulleys F—see Figs. 3 and 9—for ropes which may be utilized for any desired purpose.

The collars a', a² and a³ are provided—see Figs. 2 and 100

3—with clamping screws G by which the sections of the uprights may be held extended to any desired extent.

At their upper ends, the upper sections of the uprights support at their upper ends the platforms H, which may be provided with hand rails H'. These platforms—see Figs. 1 and 3—are provided centrally with openings coinciding with the bores of the uprights, and have on their under sides ring-like flanges 10 H² fitting over the collars a⁴, and the upper ends of the top section A⁴ may be closed if desired by plugs I—see Figs. 2 and 9—or where desired, nipples I'—see Figs. 1 and 3—may be screwed into the upper ends of the collars a⁴ and have their threaded ends extending 15 above the platforms H to receive hose sections when it is desired to utilize the apparatus for fire extinguishing purposes.

The uprights are provided at their upper ends with the laterally extending arms J braced if desired by the 20 strut braces J', and these arms are supplied at their outer ends with pulleys J², near their inner ends with the pulleys J³, and on their outer sides between their ends with the pulleys J⁴ and J⁵. The pulleys J² and J³, together with coöperating ropes j² and j³, may be 25 utilized for raising an upper shield section C⁵ and for adjusting the same at an incline—see Fig. 2—so it may be moved over an inclined roof, as will be understood from Fig. 2, in order to protect a roof from fire. The pulleys J⁴, together with ropes j⁴ may be used for manipulating a scaffold L, when it is desired to use the 30 invention in ordinary building operations, and the pulleys J⁵ and ropes j⁵ may be utilized for raising and lowering an elevator car M, which may be utilized in building operations or for fire escape purposes, and 35 when this elevator car is used in connection with the scaffold L, the latter may preferably be cut away at one end to afford an opening L' through which the car may operate.

The shield sections C may be connected together 40 by means of rings N, or other suitable devices, so the ropes F may be utilized to pull all of the sections C up after the uprights have been extended, or the said sections may be applied and connected from time to time as the sections are extended by the application

of fluid pressure. These sections C may be made of 45 sheet iron, or of any suitable material, properly covered with asbestos in order to render the same fire-proof.

I claim—

1. The combination substantially as herein described of 50 the uprights composed of the telescopic sections operating one within the other and provided at their lower ends with upwardly facing shoulders and at their upper ends with downwardly facing shoulders and having above the upwardly facing shoulders packing rings and bands above 55 the same whereby to prevent the escape of fluid between the sections, the lower section having an inlet for fluid pressure, props in connection with the lower section for steadyng the same, means on the upper section for the connection of guy ropes, a lateral arm on the upper section, means in connection with said arm for raising and adjusting a shield section laterally over a roof, and shield sections operating in connection with the telescopic sections, substantially as set forth.

2. The combination in a fire shield, of sectional telescopic uprights and a shield composed of sections brackets at the upper and lower ends of the shield sections and means securing said brackets to the sections of the uprights, substantially as set forth.

3. The combination of sectional telescopic uprights 70 provided with lateral lugs, fire shields corresponding to the sections of the uprights and provided at their meeting edges with brackets having flanges fitting between the lugs of the upright sections and a pin for securing said flanges between said lugs, substantially as set forth.

4. A fire shield comprising the uprights spaced apart, the shield sections extending between the same and the platform mounted on and extending laterally from the uprights and means for adjusting a shield section laterally 75 out below the platform, substantially as set forth.

5. The combination of the sectional telescopic uprights provided at their upper ends with the lateral arms 80 provided at their outer ends with pulleys, a shield section and a rope operating in connection with the pulleys on the lateral arms for adjusting the shield section over a roof, substantially as set forth.

6. A fire shield comprising sectional telescopic uprights, means in connection with each of the sections of the uprights for securing shield sections, shield sections corresponding to said sections of the uprights, and lateral arms 90 at the upper ends of the uprights and means operating in connection with said arms for adjusting a shield section laterally over a roof, substantially as set forth.

SOLOMON GERMAN.
